COMBINED ARM REST AND STORAGE CONTAINER FOR TAPE CARTRIDGES

Anthony Di Vona, 27 Hawthorne St., Selden, N.Y.
11784, and William Eckelkamp, 29 Peak St., Ronkonkoma, N.Y. 11779

Filed Nov. 28, 1967, Ser. No. 9,571

Term of patent 14 years

(Cl. D87—1)

FIG. 1

FIG. 2

FIG. 3

FIG. 4

FIG. 5

FIG. 6

FIG. 7

FIG. 1 is a top plan view of our design.

FIG. 2 is a right side elevational view of our design.

FIG. 3 is a rear elevational view of our design.

FIG. 4 is a front elevational view of our design.

FIG. 5 is a left side elevational view of our design.

FIG. 6 is a bottom plan view of our design, and

FIG. 7 is a perspective view of our combined arm rest and storage container for tape cartridges and showing the same with its cover in open position.

The small groups of shading lines on the cover of the box in the drawings indicate the surface texture of the cover.

We claim:

The ornamental design for a combined arm rest and storage container for tape cartridges, as shown and described.
